UNITED STATES PATENT OFFICE.

JOHN L. HEALD, OF SAN FRANCISCO, CALIFORNIA.

COMBINED HARVESTING AND THRASHING MACHINE.

SPECIFICATION forming part of Letters Patent No. 509,082, dated November 21, 1893.

Application filed September 9, 1892. Serial No. 445,433. (No model.)

To all whom it may concern:

Be it known that I, JOHN L. HEALD, a citizen of the United States, residing in San Francisco, San Francisco county, State of California, have invented certain new and useful Improvements in a Combined Harvesting and Thrashing Machine, as set forth in the following specification and the drawings forming a part thereof, which I hereby declare to be a full, clear, and exact description of my invention and the means of its application.

My invention relates to what are called combined harvesting machines, to reap, thrash and winnow grain, at one operation, and especially to that part thereof, commonly called the shoe, consisting of a vibrating riddle and a chute or guide below the riddle, on which the grain falls when it is separated from the chaff and straw, and is thereby guided or conducted to a conveyer trough.

My invention consists in means for supporting these parts called the shoes, on a pivotal support, longitudinally, so that they may freely change their plane transverse to the main machine within which they are mounted, and in means to keep these parts level transversely, or nearly so, when the machine is moving on unlevel ground, by means of suspended weights or other automatic apparatus, so connected by suitable devices that they will by their gravity and pendent position, maintain the pivoted shoe in its normal position transversely, and also longitudinally, when the latter adjustment is required.

The objects of my invention can be explained by saying that while the reaping and thrashing elements of these combined machines are not much affected by the positions assumed in passing over unlevel ground, the winnowing elements are much affected thereby.

To secure efficient operation of machines of this kind, it is essential that the grain, straw and chaff or the material to be operated upon, be distributed uniformly over the surface of the riddle, because this determines the action of the wind thereon. If the material is thin at any part of the riddle's surface it is blown off, and on the contrary, if the material is banked or piled up at either side or in any particular part, the wind is obstructed, and

the cleaning action impeded or stopped thereby, the completeness of this winnowing process being in fact, dependent on the uniformity with which the blast can be applied to the material to be acted upon. On shaking surfaces, such as the riddle forming the main part of the shoe, the slightest change from a level position, transversely, causes the material to slide to the lowest side, and thus prevents a proper action of the cleaning blast, through the riddle, to carry off the chaff, straw, and dust. Thus it may be seen that among the various elements that go to make up a combined reaping, thrashing and winnowing machine, none are much affected by an inclination of the whole machine, longitudinally or transversely, except the winnowing part, consisting especially of the riddle to which my invention may be applied alone, and the collecting and distributing chute beneath, on which the clean grain falls after passing through the riddle and on its way to the conveyer.

Referring to the drawings, Figure 1 represents, partially in section, the winnowing parts of a combined harvesting machine, such parts as my invention applies to. Fig. 2 is an enlarged detail, showing how the riddle and chute board are arranged, to prevent the grain from escaping at their sides. Fig. 3 is a diagram, showing the operation of my invention when a machine is moving on ground slanting transverse to its course. Fig. 4 is a vertical sectional longitudinal elevation of the cleaning devices and the harvester and thrasher combined.

The main elements represented in the drawings are indicated by letters, as follows:

A is an elevator for raising the grain, straw and chaff from the thrashing to the winnowing machine or part.

B is a deflecting board or apron, on which the material falls and is distributed to the riddle.

C is the shaking riddle where the chaff, straw and dust are blown off.

D is the chute board on which the grain falls from the riddle.

E is a fan to generate the cleaning blast, indicated by arrows.

F is a cross conveyer that carries out un-

thrashed heads that pass over the riddle, so that they may be returned for rethrasing and cleaning.

5 G is another cross conveyer, to carry out the cleaned grain at the side of the machine.

H is a deflecting board to direct the blast of the fan, and distribute the wind beneath and through the riddle.

I represents links connecting the riddle and chute board and supporting the former.

J is a crank and connecting rod to impart a vibratory or shaking motion to the riddle.

K represents conveyer troughs extending across the machine.

15 L is the bottom of the machine or main frame, on which the shoe is supported.

M is a weight suspended to the bottom of the chute board to keep it level transversely.

20 N is a suspended weight to maintain the chute board and riddle in the same position longitudinally, irrespective of the position of the main machine in ascending and descending sloping ground.

25 O represents stripping combs to clear the elevator and prevent it from carrying back straw and weeds on its under side.

P is a section of the inclosing side of the main machine or its frame.

30 A² represents the traveling carriage of the combined harvester and thrasher which transports all the mechanism.

B² denotes an endless carrier which discharges upon the thrashing cylinder C².

35 D² is another endless carrier which delivers upon the elevator A.

The operation of these parts can be described as follows: In the course of the grain through the machine after thrashing, it is first carried up with the straw and chaff from 40 the thrashing cylinder by the elevator A, falls on the apron B, and then slides off on the riddle C, which has a rapid shaking motion imparted to it by the crank and connection J. The grain falls through this riddle C on the chute D, while the light straw, chaff and dust are blown off by the fan E, the material having a continuous forward movement toward the discharge end Q, by reason of the blast from the fan. Any heavy material, such as 45 heads containing grain, falls down through the fingers R to the screw conveyer F, and from there is conveyed back to be thrashed a second time. The grain falling on the chute D, slides down to the screw conveyer G, and is 50 thereby carried out of the machine. The riddle C is supported by the links I I, two at each side, attached to the chute-board D. These links I permit a free shaking motion of the riddle C, and also act as an equalizing connection, so the riddle C and chute D are maintained in the same relative position to each other. The chute-board D I mount on pivotal bearings S and T in the center transversely, so it is free to rock or turn on its longitudinal 55 axis. To the bottom of the chute-board D I suspend a weight M by means of the rod U

fastened in an eye V, so the weight is free to swing forward and back longitudinally in respect to the chute D, but not sidewise without moving or turning the chute correspondingly on its supports, so that the chute D and riddle C are at all times level transversely, by reason of the pendent weight M, as indicated in Fig. 3, when W represents a sloping ground line, and a a the supporting wheels of 70 the main machine. This weight M, and its functions, constitute the main part of my invention, because the deviations of such machines are commonly transverse to their course, reaping being done, whenever possible, on a course as nearly level as possible. In some cases, however, such machines have to ascend and descend sloping ground, and in that case I maintain the normal longitudinal position of the riddle C and chute D in the 75 same manner as before, interposing, however, a bell-crank X and curved guide Y, to the top of which is attached the pivotal bearing T. The front pivotal bearing S being stationary, any movement of the weight N, forward or 80 backward as indicated by the dotted lines in Fig. 1, raises the movable bearing T, and that end of the chute D and riddle C, accordingly. These gravity devices, consisting of the weights M and N, can be applied together on 85 the same machine, as shown in Fig. 1, or either of them can be applied independently of the other, their action being alike in each case; but, as before remarked, the transverse adjustment performed by the weight M is the 90 most important because of side tilting being most common, also because of deviation in this direction having more effect in deranging the operation of the shoe. The curved guide Y is made on a radius from the pivotal bearing S, and slides in the guides e e to prevent lateral movement. The bearings S and T may be of any kind, permitting the required movement or adjustments of the shoe. I have shown, in the present case, a pivotal 95 bearing at S, and a ball and socket one at T. 100

To prevent the escape of grain over the sides of the riddle C and the chute D, I employ flexible guards m, resting against the sides P of the main frame, and overlapping 105 the pendent guards n, preferably of sheet metal, the construction of these guards being such as to permit the extreme deviation of the shoe, as indicated in Fig. 3.

While I have shown the riddle and chute, 110 or, technically, the shoe, mounted on pivotal supports beneath, it will be evident that such pivotal supports may be applied above, and the shoe suspended, the only difference being that in any case when suspended weights are 115 employed, such as I have shown, their position must be at some distance below the point of bearing or suspension for the shoe.

As the operation of the winnowing part is 120 most affected by the position of the riddle, the weight M could by suitable mechanism 125 be connected to the riddle alone, but in the

common method of constructing such combined harvesting and thrashing machines it is preferable to combine the riddle and chute to form what is called the shoe.

5 Having thus described the nature and objects of my invention, what I claim as new, and desire to secure by Letters Patent, is—

1. In a combined harvesting and thrashing machine, the combination of the winnowing riddle, the riddle chute mounted on pivotal bearings so as to permit deviation of its level transversely, links connecting the riddle and chute to keep them in like relative position and the weight M suspended to the bottom of 15 the chute board near its lower end by means of a rod movably attached thereto so that the weight may be free to swing forward and back longitudinally in respect to the chute without moving or turning the chute correspondingly on its supports, substantially as described.

2. In a combined harvesting and thrashing machine, the combination of the winnowing riddle, the chute mounted on pivotal bearings so as to permit deviation of its level transversely, links connecting the chute and riddle so as to keep them in like relative position, a weight attached to the chute board near its lower pivotal end substantially as 25 described so that it can swing freely forward and back longitudinally in respect to the chute but not endwise, and another weight supported on the chute board near its other pivotal end, substantially as described.

3. In a combined harvesting and thrashing machine, the combination of the winnowing riddle, the chute board mounted on pivotal bearings in an inclined position so that it is free to rock or turn on its longitudinal axis, 30 the links for supporting the riddle above the chute and permitting said riddle to have a free shaking motion as well as acting to provide an equalizing connection between the riddle and the chute, a weight suspended on 35 the bottom of the chute board by means of a rod fastened pivotally to said board so that a weight can be free to swing forward and back longitudinally in respect to the chute but not sidewise, and another weight sup-

50 ported at the rear end of the chute by means of a bell crank or bent lever, substantially as specified.

4. In a combined harvesting machine, the shoe consisting of the riddle C and chute D, mounted on pivoted bearings as herein described, the rear pivotal bearing T movable vertically and connected by the curved guide Y and bell crank X to a suspended weight N so arranged that the shoe will remain in its normal position longitudinally, and the weight M suspended to the bottom of the chute board near its lower pivotal bearing S by means of rod U fastened in the eye V so that weight M may be free to swing forward and back longitudinally but not side- 65 wise, substantially as specified.

5. In a combined harvesting and thrashing machine, a chute and riddle as herein described connected by links to maintain them in like position relatively, the chute being mounted on pivotal bearings so as to permit deviation of its level transversely, a pendent weight attached to the chute and free to swing forward and back longitudinally but not sidewise and another weight supported 70 at the other end of the chute by means of a bell crank and a curved guide suitably supported and connected, all substantially as described.

6. In a combined harvesting machine, the shoe, consisting of the riddle C, and chute D, mounted on pivoted bearings as herein described, the rear pivotal bearing T movable vertically and connected by the curved guide Y, and bell crank X, to a suspended weight 80 N, so arranged that the shoe will remain in its normal position longitudinally, by reason of the weight, irrespective of the position of the main machine when ascending or descending sloping ground, in the manner substantially as and for the purposes specified and 85 set forth.

In testimony whereof I have hereunto affixed my signature in the presence of two witnesses.

JOHN L. HEALD.
